(57) CLAIM

I claim the ornamental design for a cigarette stand, as shown and described.

DESCRIPTION

FIG. 1 is an upper perspective view of the cigarette stand showing my design;

FIG. 2 is a front elevation view thereof;

FIG. 3 is a top plan view thereof; and,

FIG. 4 is a side view thereof, an opposite side view being a mirror image thereof.

The dotted lines are presented for illustrative purposes and form no part of the claimed design.
